FIG. 3.

UNITED STATES PATENT OFFICE.

THOMAS V. ALLIS, OF PITTSBURGH, PENNSYLVANIA; HANNORA E. ALLIS ADMINISTRATRIX OF THOMAS V. ALLIS, DECEASED.

PAIR-HEATING-FURNACE HEARTH.

1,334,207.

Specification of Letters Patent. Patented Mar. 16, 1920.

Application filed September 11, 1918. Serial No. 253,627.

To all whom it may concern:

Be it known that I, THOMAS V. ALLIS, a citizen of the United States of America, residing at Pittsburgh, in the county of Allegheny and State of Pennsylvania, have invented certain new and useful Improvements in Pair-Heating-Furnace Hearths, of which the following is a specification.

The present invention relates to pair-heating-furnace hearths, and is an improvement whereby the sheet or tinplate bars being heat treated are moved continuously along a hearth composed of a series of transverse metal sections or hearth skids having alined grooves, from the charging end to the discharging end of such furnaces. Means is provided whereby the length of the transverse sections composing the hearth is "standardized" or held to a uniform dimension, and the "overall" length of the furnace hearth as a whole increased or reduced by the use of raised bosses of varying thickness on the ends of the individual transverse sections as will be more fully explained hereinafter in this specification.

Other features and advantages of the present invention are similar to those of United States Patent, Number 1,034,858, pair heating-furnace hearths, dated August 6, 1912, and reissued under date of December 14, 1915, as Reissue Patent Number 14,032, invented by Thomas V. Allis. Reference is made to said reissue patent for a fuller understanding of the advantages of furnace hearths having inclined grooves for supporting the sheet or tinplate bars at an angle with the horizontal on their lower longitudinal edges and one side; and also as to the continuous handling of such bars in the hearth grooves with their abutting ends crossed so that power applied to move one piece, moves its contacting neighbor in the same sustained line and direction along the grooves of the furnace hearth.

Means are also provided by which a series of grooved transverse metal sections or skids which make up the hearth of the furnace as a whole, are held so that the longitudinal grooves remain in alinement, and the said sections also prevented from advancing longitudinally along the furnace bed, as will more fully appear as the description proceeds herein.

In the accompanying drawings forming part of this specification I have shown one

complete example of the physical embodiment of my invention constructed according to the best mode I have so far devised for the practical application of the principles of my invention.

60

Figure 1 of the drawings is a transverse vertical section on line 1—1 of Fig. 2 of a pair-heating-furnace, showing my invention in operative position therein.

Fig. 2 is a horizontal section on line 2—2 of Fig. 1.

Fig. 3 is a longitudinal section on line 3—3 of Fig. 2.

Fig. 4 is a plan view of one of the "standardized" transverse metal hearth sections 70 shown in Fig. 2.

Fig. 5 is an end view of Fig. 6, taken from the left of same.

Fig. 6 is a side elevational view of two transverse hearth sections, or skids, in operative position with respect to each other and taken from the right as seen in Fig. 5.

Fig. 7 is a longitudinal section taken on line 7—7 of Fig. 5.

The numeral 1 indicates a pair-heating-furnace provided with a fire box 2, preferably located on one side of the furnace as shown, a bridge wall 3, mechanical stoker 4, and a heating chamber 5. Leading from the heating chamber 5 are the downtake 85 flues 6, which convey the products of combustion to the stack (not shown). The heating chamber 5 is provided with the usual charging and discharging openings 7 and 8 respectively, and with lifting doors 9 and 10 therefor, for the admission and withdrawal of the sheet or tinplate bars being heat-treated in the furnace.

Within the heating chamber 5 is the furnace bed or bottom 11, on which rests the transverse hearth sections 12, 13, etc., preferably formed of cast steel, comprising the whole furnace hearth 14.

Each transverse section, or hearth skid, 12, is cast with a plurality of parallel 100 grooves 15, 15, in which the bars 22, 23 are placed so that their abutting ends cross each other as shown in Figs. 1 and 2, in which it is seen the pile of bars marked 22 and 23 alternately cross each other as they lie in the 105 said grooves. It is seen from the Fig. 2 that when the end bars 22 adjacent to the charging end 7 are advanced by use of a power "pusher" or other means, that a full longitudinal series of bars 22, 23, etc., simultane-

110

ously advance toward the discharging end 8; and further the full collection of bars upon the furnace hearth 14 can likewise be simultaneously advanced over the skids 12 by advancing all the bars 22 which lie in a transverse row of grooves, adjacent to the charging end 7 of the furnace. When the bars 23 nearest the discharge end 8, which lie in the transverse row of grooves of the hearth skids 13, are withdrawn as being sufficiently heated, a new and cold transverse series of bars can be entered in the grooves 15 from the charging end 7 of the furnace. And so on indefinitely the bars 15 are continuously charged, pushed forward, and withdrawn from the furnace as they become sufficiently heated, for the subsequent steps in the manufacture of the bars into sheets. The bases of the grooves 15 are cut away at 16, and the corners at 17, 18 are rounded so that the bars do not meet with any obstruction in the bases of the grooves 15 as they are pushed along said grooves.

It is further seen that in the manipulation or "turning over" of the plates from a position such as indicated by 22 in Fig. 1, to a position 23, that the same is greatly facilitated by the wide, cut-out and rounded grooves 16 shown in the drawing, and particularly well illustrated in the Figs. 4 and 5. Stiffening ribs 19, 19 are provided, preferably at the edges 20, 20 of the section 12 of a form as indicated at 44, 45 of the Fig. 7, and under the bases of the grooves 15 there are convex bosses 21, formed as shown to transfer the weight of the bars 22, 23, etc., to the furnace bed 11. Similarly at the sides 24, 24 of each transverse metal section 12, the ribs 19 are extended downwardly at 25, 25, slightly below the bottom of the bosses 21, as seen in Fig. 1. The ribs 19 are also cut away at 26 to admit the cross-section of the centering bar 27. The purpose of the centering bar 27, which is preferably of cast metal, is to maintain the grooves 15, of the several hearth skids 12, in longitudinal alinement for the ready passage of the sheet and tin plate bars through them from the charging end 7 to the discharging end 8 of the furnace. The centering bars 27 are preferably formed of a double T cross-section, provided with strengthening webs 28, 28, and are "grouted" rigidly into the furnace bed 11. The said bars 27 are of such length as will allow the skids 12 to slide along them when expansion or contraction takes place due to temperature changes. The hearth skids are molded with concavities 29 under each apex 30, and between the ribs 19, 19 to save weight.

Each groove 15 of the skids 12, it will be seen is beveled on the charging side 31, in two directions horizontally at 32, 32 and vertically at 33, forming an outwardly and downwardly flaring mouth in each of the

grooves 15 for the more facile entrance of the sheet or tinplate bars 22, 23 into said grooves.

On each of the edges 20, 20 of each transverse section or hearth skid 12, 13, etc., a plurality of raised, and preferably semi-spherical bosses 34, 35 are formed for a purpose as will be explained below. On the skids 13 I have shown a pair of downwardly projecting lugs 36 formed preferably as extensions to the ribs 19, and these lugs 36 only occur on the discharge end 37 of the section 13 nearest the discharge opening 8. The said lugs 36 are "let into" the brickwork of the furnace bed 11, so that when the bars 22, 23 which are piled in the sections 12, 12, etc., are advanced from the charging end 7 toward the discharge end 8 of the furnace by means of a power "pusher," or otherwise, the forward thrust of the various sections 12, 12, etc., which bear against the skid 13, is transmitted to the furnace bed 11 by means of the lugs 36.

One of the most important features of my invention is its adaptability for use in making up hearths 14 of varying lengths, by using transverse sections 12 of one uniform length in conjunction with separating bosses 34, 35 of varying thicknesses as indicated by the dotted boss 38 and boss 35 of Fig. 6. This feature is best explained by an example such as usually obtains in practice in the art involved. We will assume a hearth 14, of approximately twelve feet in length is desired from point 39 to 40 Fig. 2, and that the "standard" length of hearth skids 12, in use is fifteen inches. Nine "standard" skids having bosses 34, 35 nineteen thirty-seconds of an inch in thickness can be used, making an overall length of twelve feet and one-half inch. In a similar fashion "standard" skids of fifteen inch length, and having bosses seventeen thirty-seconds of an inch in thickness, will make up a furnace hearth having an "overall" dimension of nine feet, three and one-half inches. These examples show the adaptability of these skids to producing hearths of varying overall dimensions, which is a very important feature in practice. The saving in metal by having the interstices 41 between the sections 12, 12, etc., instead of a continuous metal hearth from points 39 to 40 is also seen to be a matter of importance.

As stated in the above Reissue Patent Number 14,032 by piling the bars in grooves having an inclination to the horizontal, transverse hearth space is economized; and by crossing the abutting ends of adjacent bars, mechanical advantage is gained in the facility with which the bars are advanced longitudinally along the grooves of the hearth. These features and advantages apply to the present invention, and it is noted that when the side walls of the grooves are

formed at an inclination of forty-five degrees with the horizontal (which is considered the preferable angle of inclination) that the side edges 42 of the bars 22 and 23 5 form a substantially uninterrupted straight line, without protruding edges, and as a result any uneven heating, and unnecessary oxidation of the edges of the bars is thereby prevented.

10 In operating my improved hearth, the bars are charged thereon as before explained through the charging end 7 of the heating chamber singly or in collection, standing either at the same or reversed inclination in 15 the grooves 15. When a full transverse row of grooves 15 are filled they are (preferably) simultaneously advanced along the grooves by a power "pusher" or other means. A second transverse row is then charged, the 20 abutting ends of each of the latter being in crossed relation with respect to the adjacent ends of the bars first charged. The whole hearth in this way is completely filled with bars, and as those on the hearth skids 25 13 are withdrawn through the discharge doors 10, cold bars are introduced through the charging door 9, and in this way the heat-treatment of the bars is equal and continuous. All the bars in this way pass 30 through the same zone of heat, for a like time period, and consequently very uniformly heated bars are continuously produced, which it is well understood is a desideratum much desired in this art.

35 It is understood that each of the grooves 15 is so proportioned as to width and depth that the distance from the surface 43 against which the lower edges of the sheet bars 22 bear, to the apex 30, is always 40 greater than half the width of the bars 22 being treated so as to maintain the latter in stable equilibrium. In practice the grooves are made of such dimensions that the largest size bars can be safely supported 45 and the same hearth can then be used for smaller sized bars.

From the above it is seen I have provided a very useful and convenient form of hearth adapted to be used to make up hearths of 50 varying sizes by using transverse sections or skids of substantially uniform length, and possessing the other features and advantages above set forth.

What I claim is:—

55 1. A transverse hearth skid provided with a plurality of grooves adapted to support a number of sheet bars in an inclined position therein, stiffening ribs under the grooves, and spacing bosses on said ribs projecting beyond the end faces of the said skids.

2. A transverse hearth skid having grooves for supporting a plurality of sheet bars in an inclined position therein, stiffening ribs under the grooves, outstanding

spacing bosses on the end faces of the skid, and a number of downwardly projecting extensions on one of the stiffening ribs aforesaid.

3. A transverse hearth skid provided with 70 grooves for supporting a number of sheet bars in an inclined position therein, cut-away and rounded base portions formed in the grooves, and outwardly and downwardly flaring mouths connecting with the 75 same, the said base portions and flaring mouths of said grooves being designed to facilitate the ready entrance, free passage and manipulation of sheet bars in and along the hearth skid grooves.

4. A transverse hearth section provided with grooves having cut away rounded bases and beveled mouths, adapted to support a plurality of sheet bars in an inclined position therein, stiffening ribs beneath the 85 grooves, and outstanding spacing bosses on the ends of the said section.

5. A grooved furnace hearth composed of a plurality of transverse sections having a common length dimension, adapted to support a number of sheet bars in an inclined position, and spacing means for holding the 90 said sections a fixed distance apart.

6. A furnace hearth composed of a number of grooved sections adapted to be arranged transversely of the furnace, for holding a longitudinal series of sheet bars in alined and inclined positions, a plurality of centering bars mounted in the furnace bed slidably engaging the ends of adjacent 95 sections, and a number of downwardly projecting lugs formed on the sections and engaging the furnace bed to prevent longitudinal movement of said hearth sections along the furnace bed.

7. A furnace hearth composed of a number of transverse sections provided with a plurality of grooves for supporting a longitudinal series of sheet bars having their adjacent ends crossed, in a condition of stable 110 equilibrium therein, means for holding the grooves in alinement, and means for varying the distance between the sections to form hearths of different lengths.

8. A furnace hearth composed of a plurality of grooved transversely disposed sections adapted to support a longitudinal series of sheet bars in an inclined position, and means for varying the distance between the sections to form hearths of variable overall lengths.

9. A furnace hearth composed of a plurality of grooved transverse sections adapted to support a longitudinal series of sheet bars in an inclined position, a number of centering bars mounted in the furnace bed slidably engaging the ends of adjacent sections, and means for varying the distance between the sections to form hearths of variable overall lengths.

10. A furnace hearth composed of a plurality of hearth skids having grooves with cut away base portions, and outwardly flaring mouths, adapted to support a longitudinal series of sheet bars in inclined positions, said sections being arranged transverse of the direction of movement of the said bars through the furnace, in combination with means on the hearth skid nearest the discharge end of the furnace, engaging the bed of the furnace to prevent forward movement of the skids when the sheet bars are advanced along the grooves of the same.
11. A transverse hearth skid having grooves for supporting a plurality of sheet bars in an inclined position therein, stiffening ribs under the grooves, and a number of downwardly projecting extensions on one of the stiffening ribs aforesaid.
- In testimony whereof I affix my signature 20 in the presence of two witnesses.
